(57)

CLAIM

The ornamental design for a shoe, as shown and described.

DESCRIPTION

FIG. 1 is a front perspective view of a shoe showing my new design;

FIG. 2 is a side view thereof;

FIG. 3 is a top view thereof

FIG. 4 is an opposite side view thereof; and,

FIG. 5 is an opposite side front perspective view thereof. The broken lines depicting the remainder of the shoe form no part of the claimed design.

1 Claim, 5 Drawing Sheets
